UNITED STATES PATENT OFFICE.

FRANCIS H. SCANTLEBURY, OF BROOKLYN, NEW YORK.

ILLUMINATED SIGN.

Application filed November 3, 1936. Serial No. 310,976.

This invention relates to illuminated signs consisting of one or more sheets of glass bearing a design or configuration which has been etched or sand-blasted into the surface of the 5 glass and which is illuminated by refracted light from a source placed at one or more edges of the sheet or sheets.

It is a well known optical principle that light rays entering the edge of a polished 10 sheet or plate of glass will be transmitted through the body of the glass without being visible at either plane surface. If, however, the plane polished surface is incised by etching or sand-blasting, the indented surface 15 which consists of minute facets and other irregularities, will intercept the internally transmitted light rays and will refract and reflect the intercepted rays outwardly in a manner to brilliantly illuminate the etched 20 design or configuration. I have embodied this well known phenomenon in my illuminated sign but in a manner heretofore unknown.

Prior to my invention it was proposed to 25 construct illuminated signs of two juxtaposed sheets of glass each bearing separate parts of etched matter to be exhibited, these parts being made to appear in different colors by means of different colored transparent strips 30 interposed between the light source and the edges of the glass sheets.

One object of my invention is to provide 35 an illuminated sign wherein varying depths of color and shade effects are exhibited as desired in any portion of the design. Another object is to provide a pictorial design or representation of an object wherein the different elements or portions of the composite design are exhibited in different colors. A further 40 purpose is to provide a sign structure in which the illuminated signs are in the form of interchangeable units or packs, thereby permitting the subjects to be readily changed.

In the following description I shall refer 45 to the accompanying drawings in which—

Figure 1 is a perspective view of an illuminated sign embodying my invention;

Figure 2 is a top plan view of the same;

Figure 3 is an exploded view showing the 50 separate plates, partly fragmentary, which are assembled in the sign unit or pack to form the complete design;

Figure 4 is a fragmentary view showing a portion of the opaque backing plate;

Figures 5, 6 and 7 are respectively frag-

ments of the corners of the glass plates showing the edges exposed to the rays of the lamp;

Figure 8 is a vertical section through the opaque backing plate;

Figures 9, 10 and 11 are respectively sectional views of the lines 9—9, 10—10 and 11—11 of Fig. 3;

Figure 12 is a perspective view of a fragment of the plate 3a;

Figure 13 is an end elevation, mostly in 65 section of one form of my invention having the lamp above the sign plates;

Figure 14 is a vertical sectional view of another form of my invention in which the lamp is below the plates;

Figure 15 is a perspective view of the frame portion of a sign unit or pack;

Figure 16 is a fragmentary vertical sectional view of one end of a pack; and

Figure 17 is a fragmentary, vertical, longitudinal sectional view of the lower portion of the illuminated sign shown in Fig. 14.

In Figs. 1 to 7, I have illustrated one embodiment of my invention as applied to a multi-color sign embodying a pictorial design having the light source, indicated by the incandescent lamps 2, enclosed in the housing or lighting chamber 3, below the glass sign plates or sheets. The rectangular hollow frame 5, which holds the sign plates is preferably made of sheet metal integral with the lighting chamber, which in this form also constitutes the base or support.

I prefer to assemble the plates of the sign by inserting them in the proper relation into a skeleton frame 6, open at the top and bottom with closed sides, as illustrated in Fig. 15. The plates are supported upon inwardly directed flanges 7 at the bottom of the side members. After the plates have been inserted, they are locked by bending the tabs 8, projecting from the upper edges of the frame, down against the plates as indicated in Fig. 16, thereby forming a sign pack which may be inserted as a unit into any suitable sign frame.

The skeleton frame 6 is preferably provided with offsets 10 at the upper corners which engage the upper edges of the casing frame to support the sign pack. It is important to prevent the passage of any light rays between the casing 5 and the skeleton frame 6 since this would interfere with the bold relief and brilliancy of the sign characters. For this purpose the upper and lower casing members are provided upon the inner side

with longitudinal grooves 12 and 13 to receive corresponding beads 14 and 15, stamped in the skeleton sign frame. These interfitting parts also serve to securely hold the sign pack 5 in the casing.

The electric lamps are supported within the lighting chamber by means of suitable brackets 19, carried by a detachable member 20 which may be removed by loosening the 10 screw 21 and swinging the member downwardly until the lugs 23 may be disengaged as indicated in Fig. 17. When it is desired to suspend the sign from the top, the lighting chamber is placed above the plates as shown 15 in Fig. 13.

As pointed out above it has heretofore been proposed to provide illuminated signs wherein different objects or separate and distinct features of the sign were placed upon different 20 sheets and lighted in different colors. Prior to my invention, however, no signs have been produced having component elements or parts of a single figure, displayed in a plurality of colors to produce a pictorial 25 effect; nor have any prior illuminated signs been provided which produce shadow effects and varying depths of color or tone.

For the purpose of explaining my invention I have illustrated in Fig. 1 a pictorial 30 design embodying an old woman in Dutch attire carrying a club in her upraised hand, different parts of this figure being shown in blue, red and white colors respectively.

The dress is exhibited in blue, the folds or 35 plaits of the skirt contrasting strongly with the parts in shadow. In order to produce this effect the dress portion is cut or etched, preferably with a sand-blast, in the glass plate 3^a in the manner shown at the top of Fig. 3. I 40 regard sand-blasting as one method of etching and have so used the term "etching" in the description and claims. Those portions which are to produce the high lights of the figure and be more strongly illuminated, are 45 first cut or etched by sand-blasting to a certain depth, while the remaining portions are protected by a shielding medium. The protecting covering is then removed from the previously shielded portions and the whole 50 figure of the dress is subjected to the sand-blast until the parts which are to receive less illumination are cut to the desired depth. During this second step the portions previously etched will be cut still deeper. The 55 first cutting will be so gauged or regulated that the combined effect of the two applications of the sand-blast will produce the proper contrasting effect between the high and low lights of the design. This appears more 60 clearly in the enlarged fragmentary view shown in Fig. 12. I may also produce still further gradations in color and shading effects when it is necessary to produce desired 65 effects. Thus in the second cutting, certain 70 portions of the design may remain shielded

and these parts may be subjected to an initial cutting while the first and second cuttings are subjected to a further cutting operation. The effects produced in this manner by a plurality of cutting or etching operations are surpassingly beautiful and are entirely new in the 75 art of illuminated signs.

The woman's stockings and the club which are to appear in red are etched or cut in sheet 3^b; while those parts which are to appear in white or uncolored are etched in plate 3^c, that is, the woman's bonnet, arm, apron and shoes.

The particular color of the light rays which traverse any plate are determined by a thin transparent film embodying the desired color and applied directly to the edge of the plate. Various media may be employed for this purpose, such as the transparent shellac known as "lamp lacquer" used in coloring electric lamps. The coloring may be applied as a 85 glaze which is fired on the edge of the plate. I have indicated in Fig. 5 that a blue lacquer is applied to the lower edge of the plate 3^a and have indicated in Fig. 6, a red lacquer applied to the lower edge of plate 3^b. No coloring is applied to the edge of the outer plate 3^c as the elements of the design on this plate are to appear in white or frosted.

Another feature of my invention resides in the production of a multi-color design, picture or configuration in which the elements are so correlated that the illusion of solidarity and unity is unmarred. To accomplish this result the element or elements on one plate must be etched in harmony and conformity to the juxtaposed elements upon the other plates. Each element on one plate must, therefore, be located and positioned with relation to the elements on the other plates so that the composite picture, design or configuration presented by the assembled plates will be unitary and unbroken. The outlines of the elements of the pictorial design are counterparts of each other along contiguous edges and make edge to edge contact 100 in the picture or design. These contiguous parts may in some cases overlap to an 105 considerable extent or may even be separated to a slight extent.

A further feature of this phase of my invention consists in positioning the respective elements of the design in a manner to produce the effect of naturalness and solidarity. This gives an aesthetic quality to the picture which is not only pleasing but greatly enhances the 115 artistic beauty of the ensemble. Thus in the example shown, the woman's dress is etched upon the rearmost plate, while the apron which overlies the dress is etched in the front plate. Likewise the arm and shoes are carried by the front plate while the stockings and club are placed on the intermediate plate which is back of the front plate.

It will also be noted that I am enabled to produce the effect of solidity and to a certain 120

extent of thickness and rotundity by the fact that the different portions of the picture or design which are superposed, are supported in parallel planes.

5 The optical principles involved in the production of edge illuminated etched plates are well known and need not be described. I have taken advantage of the optical laws or phenomena, however, in a manner which is 10 new in this art. By etching certain portions deeper into the plate I have produced new effects. The more deeply cut areas intercept a larger amount of the transmitted light rays and also greatly increase the number of 15 facets and irregularities in the frosted surface which refract and reflect the light outwardly. In this manner I am enabled to produce high lights and shadows, varying degrees of color intensity and tone effects here- 20 tofore unknown. The intensity of the internally transmitted light is enhanced by the polished edges of the plates which reflect the light rays back into the plate and I may increase the intensity of this reflection by sil- 25 vering the edges.

It is important that no light shall penetrate the sign plates from the rear and hence I provide an opaque backing plate 25. This also absorbs any extraneous light from within 30 out the sign and causes the design or characters of the sign to stand out in bold relief.

It is obvious that I may mount the plates of different signs upon opposite sides of the opaque plate thus providing a double sign 35 lighted from the same source.

I have discovered that the opaque backing sheet may be employed to establish a ground color to bring out contrasts and color effects in association or combination with the various 40 colors transmitted from the edge lighting. Moreover, since the various colored light rays transmitted through the respective plates do not penetrate each other, I have found that 45 different effects and different degrees in contrasts may be produced by varying the color of the background as by overlaying a solid background of any given color in part with another color.

In Figs. 8 to 11 I have vertical sectional views of the several plates of the sign described herein. When these plates are assembled within the skeleton frame shown in Fig. 15 and secured by bending down the end tabs 8, a sign pack is formed which can be transported as a unit and inserted into one of the 55 sign casings or housings shown in Fig. 1 and in vertical section in Fig. 14. The design or subject matter of the sign can be readily changed by removing one sign pack and inserting another. Thus a commercial concern 60 having branches or stores widely distributed throughout the country may change their signs from time to time by merely shipping new sign packs to be substituted for the old 65 ones. While of course the individual plates

could be inserted in the sign housing or casing, the convenience and safety of the packs or sign units will be appreciated.

I claim:

1. A multi-plate sign of the edge illuminated type having a composite configuration adapted to be illuminated in a plurality of colors, comprising a plurality of juxtaposed glass plates, each plate having etched therein a portion of the composite configuration, 75 and at least one plate having an adherent colored transparent coating on one edge.

2. A multi-plate sign of the edge illuminated type having a composite configuration adapted to be illuminated in a plurality of 80 colors, comprising a plurality of juxtaposed glass plates, each plate having etched therein an element of the configuration, certain of said plates having an adherent colored transparent coating on the light transmitting 85 edge, and a frame adapted to hold said plates and to position them with the elements in proper registry in the composite configuration.

3. In a sign as set forth in claim 2, an 90 opaque backing plate positioned against the rear plate to establish a ground color for the illuminated configuration.

4. In a sign as defined in claim 2, the edges other than the light transmitting edge, having 95 inwardly directed mirrored surfaces to thereby reflect the light rays transmitted edgewise through the plates.

5. A sign comprising a transparent glass plate having a character etched in its surface 100 which is adapted to be illuminated by light rays transmitted through an edge of the plate, said character having areas of varying depth to thereby refract the light rays with different degrees of intensity.

6. An illuminated sign comprising a pack 105 of juxtaposed transparent plates secured together, each plate bearing an incised configuration having a refracting surface forming an element of a design, the design elements on the several plates being positioned in such relation to each other that the ensemble exhibits the complete design, the contiguous edges of certain of said plates along one side of the pack having an adherent transparent colored coating, a lighting chamber enclosing said contiguous edges and a source of light within said chamber.

7. In an illuminated sign as set forth in 110 claim 6, certain of said plates having portions of the design elements incised to different depths to thereby refract with different degrees of intensity the light rays transmitted edgewise through the plates.

8. An illuminated sign comprising a pack 115 of juxtaposed transparent plates secured together in a frame, each plate bearing an etched configuration forming an element of a composite design, the design elements on the several plates being positioned in such 120 130

relation to each other that the ensemble exhibits the complete design, the contiguous edges of certain of said plates along one side of the pack having an adherent transparent colored coating, a skeleton housing adapted to receive said pack, said housing having a lighting chamber provided with an opening extending longitudinally of and adjacent to said contiguous edges of the plates, and a source of light within said chamber.

9. In an illuminated sign as specified in claim 8, means to exclude extraneous light from the edges of the plates.

10. A multi-plate sign of the edge illuminated type embodying a pictorial design adapted to be illuminated in a plurality of colors, comprising a plurality of juxtaposed glass plates, each plate having incised therein an element or elements of the design, the outlines of adjacent elements being counterparts of each other along contiguous edges, and the edges of certain of the plates being provided with an adherent colored transparent coating.

11. A multi-plate sign of the edge illuminated type embodying a pictorial design adapted to be illuminated in a plurality of colors, comprising a plurality of juxtaposed glass plates, each plate having incised there-

in an element or elements of the design, the outlines of adjacent elements being counterparts of each other along contiguous edges, the latter having an edge to edge contact in the design, and the edges of certain of the plates being provided with an adherent colored transparent coating.

12. A multi-plate sign of the edge illuminated type having a composite configuration adapted to be illuminated in a plurality of colors, comprising a plurality of juxtaposed glass plates, each plate having etched therein an element of the configuration, certain of said plates having an adherent colored transparent coating on the light transmitting edge, a frame adapted to hold said plates and to position them with the elements in proper registry in the composite configuration, and an opaque backing plate positioned against the rear plate to establish a ground color for the illuminated configuration, said backing plate being of suitable colors to co-act with light rays transmitted through the coated edges of the plates in producing desired color effects in the composite configuration.

In testimony whereof I affix my signature.

FRANCIS H. SCANTLEBURY.
